UNITED STATES PATENT OFFICE.

CHARLES W. MCCORMICK, OF EMPORIA, KANSAS, ASSIGNOR TO LAMSON CONSOLIDATED STORE SERVICE COMPANY, OF NEWARK, NEW JERSEY, A CORPORATION OF NEW JERSEY.

STORE-SERVICE APPARATUS.

SPECIFICATION forming part of Letters Patent No. 726,089, dated April 21, 1903.

Application filed June 24, 1901. Serial No. 65,759. (No model.)

To all whom it may concern:

Be it known that I, CHARLES W. MCCORMICK, of Emporia, in the county of Lyon and State of Kansas, have invented certain new and useful Improvements in Store - Service Apparatus, of which the following is a specification.

My invention relates to new and useful improvements in store-service apparatus; and its object is to provide a better means for supporting the track at desired points.

My invention consists of certain novel features hereinafter described, and particularly pointed out in the claims.

In the accompanying drawings, which illustrate a construction embodying my invention, Figure 1 is a side elevation of a store-service apparatus embodying my invention. Fig. 2 is a detail view showing the position of the tracks and carrier *en route* passing the first support. Fig. 3 is a similar view showing the position of the tracks and carrier *en route* in the same direction passing the second support.

Like letters of reference refer to like parts throughout the several views.

The track-wire A is connected to the trap B of the usual construction at its opposite ends. Located along the track-wire A are two supports C C', to which the track-wire is connected in the usual way, and connected to said supports is a chain D, by means of the fingers C³ C⁵, pivoted to the bridges C C' at C² and C⁴, respectively, and said chain passes over suitable pulleys E, secured to the ceiling. The trap B at each end is provided with a carriage G, adapted upon pulling on the cord H to be raised and lowered on the standard F, secured to the ceiling. When it is desired to despatch a carrier, say, from the left hand to the right, the cord H is pulled down by the operator and the carriage G is raised until it is engaged and held by the catch J, secured on the standard F, and the carrier A' is despatched by gravity along the track-wire A. The carrier traveling down the track-wire A reaches the position shown in Fig. 2 on the first bridge C, with the bridge pulled down by the weight of the carrier, and the

carrier continues its travel along the track-wire A, and after leaving the bridge C as it approaches the bridge C' a reverse action takes place, as will be seen in Fig. 3, wherein the second bridge C' is pulled down by the weight of the carrier and its load, and the carrier continues its travel. The descent on the loop H' is controlled by the governor K in the usual manner. Connected to the catch J at the left hand of the drawings is the wire L, known as a "trip-wire," which passes the bridge C and is connected to the eye D² of the finger C⁵ and is secured to the ceiling by the screw L'. When the carrier A' is passing the bridge C', Fig. 3, it depresses the bridge, which pulls down the trip-wire L, secured to the upper end of the catch J, and moves said catch to release the carriage G, which drops to its normal position, (shown in Fig. 1, right-hand end,) its descent being controlled by the governor K. The wires L and M cross one another on opposite sides of the chain D and between the bridges C C', as indicated in Fig. 1. When the carrier has reached the right-hand end of the line and it is desired to send it to the left-hand end, the operation is identical with that described for a carrier going from left to right, and as the carrier reaches the bridge C it pulls down said bridge, and with it the trip-wire M, connected at the right-hand end to the catch J and at the left-hand end to the screw-eye M'. This pulling down on the bridge releases the trip from its upper position at the right of Fig. 1, and the carrier assumes its normal position at the bottom of the standard F, the governor K controlling the descent in the usual manner.

By the construction above described I have reduced the sag occurring in long lines where there is no intermediate support to the track-wire. Also in long lines where there is a rigid support intermediate of the ends I have avoided the abrupt hill formed by the track-wire where it is connected to the support, as all the sag is carried forward to the point of connection of the support to the track-wire in case of a rigid support. Aside from the foregoing reasons there is a necessity for a support, inasmuch as in extremely long lines

the tension is so great upon the track-wire and its braces that there is more or less danger of accident in carrying heavy packages, and it will be readily seen that this is 5 reduced by the intermediate yielding supports, as shown and described.

I do not limit myself to the arrangement and construction shown, as the same may be varied without departing from the spirit of 10 my invention.

Having thus described the nature of my invention and set forth a construction embodying the same, what I claim as new, and desire to secure by Letters Patent of the United 15 States, is—

1. In a store-service apparatus, a track, a support for the track at its opposite ends, and an intermediate yielding support connected at its opposite ends to the track.
2. In a store-service apparatus, a track, a vertically-movable carriage to which the track is secured, means for raising said movable carriage, a catch for retaining the carriage in its upper position, a carrier adapted to travel 25 by gravity along said track, a yielding intermediate support for said track, and means operated by the movement of the yielding support to release the carriage to allow it to return to its normal position.
3. In a store-service apparatus, a track, a vertically-movable carriage to which the track is secured, means for raising said movable carriage, a catch for retaining the carriage in its upper position, a carrier adapted to travel 35 by gravity along said track, a yielding intermediate support for said track, and a trip-wire operated by the movement of the yielding support to release the carriage to allow it to return to its normal position.
4. In a store-service apparatus, a track, a vertically-movable carriage to which the track is secured, means for raising said movable carriage, a catch for retaining the carriage in its upper position, a carrier adapted to travel 40 by gravity along said track, a yielding intermediate support connected to the track at two points, and a trip-wire operated by the movement of the yielding support to release

the carriage to allow it to return to its normal position.

5. In a store-service apparatus, a track movable at each end, a vertically-movable carriage to which each end of the track is secured, means for alternately raising each end of the movable track, a catch for holding the 55 lifted carriage in its upper position, a carrier adapted to travel by gravity along said track from one end to the other, a yielding support for the track, and means operated by the movement of the yielding support for releasing the carriage at that end from which the carrier has been despatched.

6. In a store-service apparatus, a track movable at each end, a vertically-movable carriage to which each end of the track is secured, means for alternately raising each end of the movable track, a catch for holding the 60 lifted carriage in its upper position, a carrier adapted to travel by gravity along said track from one end to the other, a yielding support 70 connected to the track at two points, and means operated by the movement of the yielding support for releasing the carriage at that end from which the carrier has been despatched.

7. In a store-service apparatus, a track movable at each end, a vertically-movable carriage to which each end of the track is secured, means for alternately raising each end of the movable track, a catch for holding the 80 lifted carriage in its upper position, a carrier adapted to travel by gravity along said track from one end to the other, a yielding support connected to the track at two points, and a trip-wire operated by the movement of the 85 yielding support for releasing the carriage at that end from which the carrier has been despatched.

In testimony whereof I have signed my name to this specification, in the presence of 90 two subscribing witnesses, this 20th day of June, A. D. 1901.

CHARLES W. MCCORMICK.
